MODULAR UNIT FOR GRILLE PANELS

Richard Harvey, 66 Denton Ave., Lynbrook, N.Y.

Filed Jan. 22, 1964, Ser. No. 78,309

Term of patent 14 years

(Cl. D13—1)

FIG. 1

FIG. 2

FIG. 4

FIG. 3

FIG. 5

FIG. 1 is a perspective view of a modular unit for grille panels, showing my new design.

FIG. 2 is a top plan view thereof.

FIG. 3 is a front elevational view thereof.

FIG. 4 is a side elevational view thereof.

FIG. 5 is a front elevational view in solid lines, of the modular unit of FIGURES 1-4, as assembled in a grille panel.

The broken lines showing a plurality of modular units are for illustrative purposes only.

I claim:

The ornamental design for a modular unit for grille panels, substantially as shown and described.
